US00D515534S

(12) **United States Design Patent** (10) Patent No.: **US D515,534 S**
 Park et al. (45) Date of Patent: **** Feb. 21, 2006**

(54) **CELLULAR PHONE**

(75) Inventors: **Dae-Yoeb Park**, Seoul (KR);
Chang-Hwan Hwang, Goyang-si (KR);
Chi-Young Ahn, Seoul (KR)

(73) Assignee: **Samsung Electronics Co., Ltd.** (KR)

(**) Term: **14 Years**

(21) Appl. No.: **29/214,450**

(22) Filed: **Oct. 1, 2004**

(30) **Foreign Application Priority Data**

Apr. 2, 2004 (KR) 30-2004-0009465

(51) **LOC (8) Cl.** **14-03**

(52) **U.S. Cl.** **D14/138**

(57) **CLAIM**

We claim the ornamental design for a cellular phone, as shown and described.

DESCRIPTION

FIG. 1 is a top and front perspective view of a cellular phone, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.
